UNITED STATES PATENT OFFICE.

GILBERT O. GULACK, OF SAN DIEGO, CALIFORNIA.

DISPLAY APPARATUS.

988,262.

Specification of Letters Patent. Patented Mar. 28, 1911.

Application filed January 10, 1911. Serial No. 601,774.

To all whom it may concern:

Be it known that I, GILBERT O. GULACK, a citizen of the United States, residing at San Diego, in the county of San Diego and 5 State of California, have invented a new and useful Display Apparatus, of which the following is a specification.

My invention relates to a display apparatus for the exhibition of goods, merchandise, and the like, its purposes being the provision of simple and efficient apparatus of new and novel construction, whereby the operator may bring a series of shelves, racks, trays, or cabinets, into a position easy of 15 access from the floor or from the display counter.

My invention is more particularly a device in which a series of shelves or display racks are suspended from a pair of chains which 20 are carried by sprocket wheels arranged in pairs on a horizontal axis, the arrangement of chains and sprocket wheels being such that the shelves are raised and lowered vertically, means being provided whereby 25 the shelves may be operated by the application of power from a hand wheel, and means being provided whereby the hand wheel mechanism may be disengaged and the shelves operated directly by the use of 30 the operator's hands.

Other objects and advantages are, a means for moving goods and merchandise from one floor to another without disturbing the shelves or the contents thereof, or the arrangement 35 of goods thereon, the ease and rapidity with which the contents of the top or any other shelf may be placed for examination by a prospective customer, being an especial feature of this invention. By this arrangement 40 or device a more compact arrangement of goods may be secured and a much larger quantity of goods may be carried in accordance with the floor space than in stores where counters and rigid shelving is used.

These and other objects and advantages are attained by the application of the invention embodied in this device, substantially as herein illustrated, described, and claimed.

Referring to the drawing which accompanies and forms a part of this specification, numeral 1, designates the horizontal shafts, which are rotatably mounted in bearings 2, carried by brackets 3, and upon which large 55 sprocket wheels 4, are mounted. These sprocket wheels are connected to sprocket

chains 5, which are arranged to move in a vertical plane, and carry a series of suspended shelves 6, which may thereby be adjusted vertically for the display of goods and merchandise. These display shelves may consist of a plain and level platform, or may be provided with a wall 7, upon the back and sides thus forming a tray, or in place of a platform shelf, a rack 8, may be substituted, whereby dry-goods and dress-goods may be displayed to better advantage. The shelves may carry closed boxes or cabinets 9, for the handling of goods which by the nature thereof are required to be kept in a closed receptacle.

To secure alinement of the sprocket chains whereby the shelves may swing freely in a suspended position, a series of rods 10, connect the two chains and the shelves are pivotally connected to these rods.

Guide wheels 11, are mounted on the rear corners of the shelves and are adapted to travel in channel irons 12, thereby keeping the shelves in a horizontal position regardless of the position of the weights or goods disposed thereon. A space in the upper end of each channel iron is provided for the passage of rods 10, and a series of guide wheels 13, are provided which are arranged vertically above guide wheels 11. Guide rails 14, engage with wheels 13, thereby keeping the shelves in alinement, and causing the guide wheels 11, to cross the space between the ends of the channel irons and reengage therewith.

As a means of operating the shelves, I provide a large worm-wheel 15, on the lower horizontal shaft 1, the worm-wheel meshing with worm 16, carried by a horizontal shaft 17, which is mounted in an eccentric bearing 18, the worm shaft 17, having a geared connection 19, with a vertically mounted shaft 20, which is provided with hand wheels 21, whereby the shelves may be brought into the desired position by the application of hand power to the hand wheels. This arrangement of a worm-wheel and worm constitutes a brake whereby the shelves may be held in position, and means for releasing the brake are employed, whereby the operator may the more quickly operate the shelves by simply grasping the shelves with the hands and raising and lowering them. This is accomplished by the eccentric bearing 18, which is operated by a rack 22, having connection with a shaft 23, the same being oper-

ated by floor buttons 24, whereby the operator may have the free use of the hands in raising and lowering the shelves. Springs 25, operate to throw the worm into mesh 5 with the worm wheel, and thereby hold the sprocket wheels and chains from rotating, regardless of the balance of the weights or goods on the different shelves.

An electric motor 27, geared to shaft 20, 10 and controlled by switches 26, is provided for the electrical operation and control of the apparatus from any floor or counter.

By the application of the mechanical means as shown, the apparatus may be used 15 for the handling of large quantities of goods or merchandise in a successful manner.

From the foregoing description it will be seen that simple and efficient means are herein provided for accomplishing the objects of 20 the invention, but while the elements shown and described are well adapted to serve the purposes for which they are intended, it is to be understood that the invention is not limited to the precise construction as set 25 forth, but includes within its purview such changes as may be made within the scope of the appended claims, and such modifications as may be made without departing from the spirit of the invention.

30 I claim as my invention:

1. In a device as described, the combination of sprocket wheels and chains, display shelves suspended from the chains, shafts carrying the sprocket wheels, means for 35 keeping the shelves in alinement, a brake wheel on the lower sprocket wheel shaft, adapted to engage with a worm, a shaft mounted in an eccentric bearing, means for rotating the bearing comprising a toothed 40 portion on said bearing, a rack engaging therewith, means for operating said rack with floor buttons, and a worm on the end of the eccentrically mounted shaft, whereby the shelves may be released and operated 45 for the purpose of displaying goods from each shelf at one counter.

2. In a device as described, a shaft carrying sprocket wheels and a worm wheel, sprocket wheels carried by another parallel 50 shaft, chains carried by the sprocket wheels, display shelves suspended from the chains, a shaft having a worm on one end engaging

with the worm wheel, and a vertical shaft mounted at a substantially right angle thereto having geared connection therewith, and 55 carrying hand wheels at one or more points, whereby the shelves may be operated from one or more floors, substantially as shown.

3. In combination with two or more floors of a building having a passage way from one 60 floor to the other, sprocket wheels upon horizontal shafts mounted at the upper and lower ends of the passage way, chains carried by the sprocket wheels, display shelves suspended from the chains, means whereby 65 the shelves may be brought into the desired position by the application of power to a hand wheel, and means whereby the hand wheel mechanism may be disengaged, for the purpose of directly operating the shelves 70 at the will of the operator.

4. In a movable display apparatus as described, the application of a worm wheel and worm as a brake, means for releasing the worm, and means for operating the same for 75 adjustment of the shelves, substantially as shown and set forth.

5. In a display apparatus, the combination of shafts, bearings for said shafts, supports for the bearings, a pair of sprockets 80 mounted on each shaft, chains which travel over the sprockets, shelves suspended from the chains, rods connecting the chains and forming pivot bearings for the shelves, guide wheels mounted on the rear corners of the 85 shelves, channel irons in which the guide wheels operate, a large worm wheel mounted on the lower sprocket wheel shaft, a worm which is adapted to mesh with the worm wheel, a horizontally mounted shaft carrying the worm, an electric motor, means 90 whereby the motor operates the worm shaft, and switches electrically wired to the motor whereby the apparatus may be operated and controlled from any floor or counter reached 95 by the apparatus, substantially as shown and described.

In testimony whereof, I affix my signature, in presence of two witnesses.

GILBERT O. GULACK.
